UNITED STATES PATENT OFFICE

HARRY H. SEMMES, OF CHEVY CHASE, MARYLAND, ASSIGNOR TO BENDIX AVIATION CORPORATION, OF NEW YORK, N. Y., A CORPORATION OF DELAWARE

AIRFOIL CONSTRUCTION

Application filed June 19, 1928. Serial No. 372,156.

The invention relates to airfoils and more particularly has reference to an airfoil which possesses great strength and rigidity.

In the past there have been two general designs employed in the construction of all metal airfoils. One method makes use of a plurality of metal ribs shaped to conform to the camber of the wing and provided with a plurality of openings to allow the spars to pass therethrough. The other design employs spars of girder form, either channels or beams, generally of built up members, and bracing members or ribs, in the form of bridge truss chords and diagonals, placed between 10 the girders normal to their longitudinal axis.

While the first mentioned construction has the advantage that the ribs support the surfacing material, it possesses the defect that the spars do not. Moreover since the spars 20 have a large cross sectional area, a large opening must be provided in the ribs to allow them to pass therethrough with the attendant result of a diminished rib resistance to any force applied to the airfoil. To overcome this, the 25 rib must be given a greater depth which results in an increase in weight of the rib.

Although in airfoils employing a frame of girder like spars with ribs normal to the girders and formed of crossed diagonals having top and bottom chord members, the surfacing material may be supported upon the ribs and girders, and the whole may be formed into a continuous structure, they possess the disadvantage that their fabrication 30 is very costly. It is well known that excluding the motor, the materials used in an airplane represent from 6% to 8% of its total cost, the principal expense being the labor. The difficulties of constructing such an airfoil may be seen to lie considerably in its multiplicity of parts, all of which must be accurately formed with a minimum tolerance limit being allowed. The ribs must be accurately cut to fit between the girders and must 35 be secured to them by special shaped fittings. Usually the girders are of built up members of the I beam type although channels are sometimes used and this requires an additional amount of accurate workmanship.

Such construction also results in an in-

crease in the weight of the girder itself due to the additional material required by the flanges of the girder so that they may be connected to the web. One of the requisites of an airfoil is that it must be light in weight. In the foregoing design, because of the necessity of the chords, the crossed diagonals and the securing fittings for them, considerable weight is given to the airfoil which reduces the useful load that can be carried to meet a specific performance.

To overcome the difficulties mentioned above, designers have employed a modified construction comprising two girders and a plurality of ribs spaced between them. However, in such a design the surfacing material is formed in wide strips and these are laid over the frame work so that their ends overlap each other and may be connected together. This design, however, presents only a small saving in the weight of the airfoil and it is nearly as difficult to fabricate.

I am aware that airfoils having an internal corrugated member or members equal in width thereto and running the full length of the airfoil have been employed in place of the spar and rib types of construction. In such an airfoil, the surfacing material is supported upon the corrugations. While airfoils of this type are of simple and continuous construction, they have the serious defect that, because of the corrugated member being equal to their full length, they possess extreme weight.

The major object of the invention is the design of an airfoil which is a continuous structure.

Another object of the invention is the construction of an airfoil provided with an internal continuous frame.

Another object of the invention is the construction of an airfoil provided with a continuous internal frame for supporting the surfacing material.

Another object of the invention is the construction of an airfoil provided with an internal continuous frame comprising a plurality of girder like spars and wavelike shaped ribs.

Another object of the invention is the con-

struction of a rib for an airfoil of wavular-like shape so that the surfacing material may be supported upon the crests and troughs of the rib.

5 Yet another object of the invention is the construction of a wavular shaped rib of relatively small thickness and width.

Yet another object of the invention is the construction of an airfoil provided with 10 girder like spars having a plurality of openings therein so as to allow the ribs to pass through the spars.

Still another object of the invention is the construction of an airfoil provided with 15 an internal frame comprising a plurality of girder like spars and ribs adapted to pass through the spars and to extend from the leading to the trailing edge of the airfoil.

Still another object of the invention is the 20 construction of an airfoil provided with an internal continuous frame of girder like spars and wavular shaped ribs, the surfacing material being supported upon and fused to portions of the ribs and to the spars for their 25 full length.

Still another object of the invention is to provide an airfoil which is of simple construction and of relatively low cost to fabricate.

30 With these and other objects in view, which may be incident to my improvements, the invention consists in the parts and combination to be hereinafter set forth and claimed, with the understanding that the several necessary 35 elements comprising my invention may be varied in construction, proportions and arrangement without departing from the spirit and scope of the appended claims.

The present invention deals with airfoils, 40 and consists in the construction of an airfoil which is a continuous structure. One method of practically effecting the concept of this invention is to support the surfacing material upon an internal frame, comprising a 45 plurality of girder like spars and wavular shaped ribs, adapted to pass through the spars and to be secured thereto.

In order to make my invention more 50 clearly understood, I have shown in the accompanying drawings, means for carrying the same into practical effect without limiting the improvements in their useful applications to the particular constructions which, for the purpose of explanation, have been 55 made the subject of illustration.

In the drawings:

Figure 1 represents a top view of the airfoil with a portion of the surfacing material 60 partially broken away.

Figure 2 represents a cross section of the airfoil showing an outline of one of the ribs taken along the line 2—2 of Figure 1.

Figure 3 is a pictorial representation showing a partial view of one of the wing spars 65 with the rib arrangement employed.

Referring to the drawings, like numerals represent like parts throughout the several views. The numeral 1 designates the surfacing material of an airfoil provided with an aileron 2 and an internal frame made up 70 of a plurality of girder like spars 3 and curvilinear or wavular shaped ribs 4. Each girder like spar 3 is of Z shaped cross section having the flanges formed integral with its web so as to do away with the use of built-up girders and their attendant high cost of fabrication. It is understood that if it is desired, girders having other sections, such as I beams and channels, may be employed without departing from the spirit of the invention. The girders 3 are spaced along the 75 transverse axis of the airfoil and have their webs positioned parallel to the longitudinal axis thereof.

Provided in each Z bar member 3 are a 80 plurality of openings 5 adapted to allow the ribs 4 to pass therethrough. Openings 5 are positioned substantially along the longitudinal neutral axis of each girder member and they are respectively spaced at equal distances. Lightening holes 6 are provided in each spar 3 if desired.

Each rib 4 has a wavular or curvilinear shaped outline, comprising a series of waves 95 of varying lengths and amplitudes having crests 7 and troughs 8 which are located substantially equidistant from any two girders. It should be noted that the rib wave of greatest amplitude is formed upon the forward 100 part of the rib, that is, forward of the longitudinal center line of the airfoil. From Figure 2, it may be observed that the forward end 9 of each rib is bent backwardly towards the trailing edge of the airfoil, while the after or rearward end of the rib is bent towards the leading edge of the airfoil, and both bent portions of each rib are shaped to conform to the airfoil contour and are parallel thereto for a substantial distance.

As shown in Figure 3 the wave outline of 110 each rib is of adjacent direction to that of any preceding rib. Thus all points on the ribs in contact with the surfacing material and lying in a line parallel to the longitudinal axis of the airfoil are alternately on the top and bottom surfaces of the wing.

Ribs 4 are adapted to pass through the 115 openings 5 and the portions thereof surrounded by the Z bar members are secured thereto.

In the construction shown the surfacing material is supported upon the leading and trailing edges and the crests and troughs of the ribs and upon the flanges of the girder like members. Since the surfacing material is supported upon and connected to the ribs and spars it takes part of the load itself and thus adds further strength to the airfoil. The girder members 3 provide transverse 120

bracing thereto besides giving additional strength to the girders.

By shaping the leading and trailing edges of each rib so that they are parallel to the contour of the airfoil for a substantial distance, strengthening qualities are given to the surfacing material supported along this area so as to resist forces of any description. By arranging each rib so that its wave outline is opposite in direction to that of any adjacent rib, it is evident that the beneficial effects of a staggered truss are obtained. Since the crests and troughs of the ribs are arranged so as to support the surface material midway between any two girders they materially aid in taking care of stresses arising in the area between any two spars. As is well known, the center of pressure in good airfoil design is located forwardly of the longitudinal center line of the wing. Moreover, the greatest forces acting upon an airfoil occur forwardly of this center line. To meet this fact, it may be observed that towards the leading edge of the airfoil, the amplitude of each wave in the curvilinear outline of the rib increases.

The embodiment of the invention allows the framework of the girders and ribs to be tied together by reason of the ribs being secured to the girders and the whole airfoil to be formed into a continuous structure by reason of the surfacing material being supported upon and connected to the leading and trailing edges and the crests and troughs of the ribs and the girder flanges. Should any particular member be stressed, a portion of its load is transmitted to every part of the airfoil and the other members carry a part of it. Hence every member has a strengthening effect upon the other members of the airfoil.

The airfoil is intended to be constructed of metal material, the ribs and girder members being of thin cross-section, while the surfacing material is of the sheet type. It is desired to employ metal which may be welded or fused. When such metal is employed, the skin of the airfoil is fused to the leading and trailing edges and the crests and troughs of the ribs and to the flanges of the girders. Similarly, the ribs are secured to the webs of the girders where they pass through them. Should it be found desirable to use metal which is difficult to weld, such as aluminum or its alloys, the airfoil skin may be secured to the ribs and girders by soldering, by the use of rivets, or by other fastenings. In a similar manner the ribs may be secured to the girders at points where they pass therethrough.

In airfoil construction, it is desirable to have means accessible to the interior of the airfoil so that the ribs and spars may be inspected. Should this feature be desired in connection with the invention, it is obvious that a portion of the upper surfacing mate-

rial of the airfoil may be formed of sheet metal and the remainder of fabric.

Although I have shown my invention as applied to an airfoil section having a flat bottom chord, I wish it to be distinctly understood that I do not limit myself to this type of airfoil. Obviously the spirit of the invention would include any kind of airfoil section, as for example a double cambered section, a section having its under surface entirely concave, or a combination of a concave and a convex section.

The features of the airfoil construction will be appreciated from the foregoing description. It may be seen that an airfoil which is a continuous structure has been formed. Moreover an airfoil, all the members of which resist strain upon any particular member and all members of which act as bracing members for each other has been developed. Finally it may be seen that an airfoil which is of simple construction and inexpensive fabrication has been designed.

While I have shown and described the preferred embodiment of my invention, I wish it to be understood that I do not confine myself to the precise details of construction herein set forth, by way of illustration; as it is apparent that many changes and variations may be made therein, by those skilled in the art, without departing from the spirit of the invention, or exceeding the scope of the appended claims.

I claim:

1. An airfoil comprising a plurality of curvilinear shaped ribs having a wave-like outline, the wave outline of each rib being opposite in direction to that of any adjacent rib and surfacing material supported upon said ribs.

2. An airfoil comprising a plurality of curvilinear shaped ribs having a wave-like outline the wave outline of each rib being opposite in direction to that of any adjacent rib, the leading and trailing ends of each rib shaped to conform to the contour of the airfoil, and surfacing material adapted to be supported upon the leading and trailing ends and the crests and troughs of said ribs.

3. An airfoil comprising a plurality of curvilinear shaped ribs having a wave-like outline the wave outline of each rib being opposite in direction to that of any adjacent rib and composed of a plurality of waves of varying lengths and amplitudes, said waves of greatest amplitude occurring forwardly of the longitudinal center line of said airfoil and surfacing material adapted to be supported upon the ribs.

4. An airfoil comprising a plurality of internal Z bar members parallel to the longitudinal axis thereof, and said Z-bar members being of a length substantially equal to that of the airfoil sheet surfacing material supported upon the flanges of said Z.bars.

5. An airfoil comprising a plurality of internal Z-bar members of a length substantially equal to that of the airfoil positioned parallel to the leading edge thereof, said bars provided with a plurality of respectively equal spaced openings along their longitudinal web axes, a plurality of ribs adapted to pass through said openings and to be secured to the bar members and surfacing material adapted to be supported upon the flanges of said Z bar members.
6. An airfoil comprising a plurality of girders, positioned parallel to the longitudinal axis thereof, the girders being provided with a plurality of respectively equal spaced openings along their longitudinal web axes, a plurality of ribs having a curvilinear outline of wave-like shape, the leading and trailing edges thereof being parallel to the contour of the airfoil for a substantial distance and surfacing material adapted to be supported upon the leading and trailing edges and the crests and troughs of said ribs and upon the flanges of said girders.
7. An airfoil comprising a plurality of metal girders positioned parallel to the leading edge thereof, the girders being provided with a plurality of respectively equal spaced openings along their longitudinal axes of the webs, a plurality of metallic ribs of curvilinear outline having crests and troughs, the leading and trailing edges thereof being parallel to the contour of the airfoil for a substantial distance, said ribs adapted to pass through the openings and to be fused to said girders and sheet metal surfacing material adapted to be supported upon and fused to the leading and trailing edges and the crests and troughs of the ribs and the flanges of the girders.
8. An airfoil comprising a plurality of girders positioned parallel to the leading edge of the airfoil, the girders being provided with a plurality of respectively equal spaced openings along their longitudinal web axes, a plurality of curvilinear shaped ribs having a wave-like outline, the wave outline of each rib being of opposite direction from that of any adjacent rib, said ribs adapted to pass through said openings and to be secured to each girder, and surfacing material, supported upon the ribs and the flanges of said girders.
9. An airfoil comprising a plurality of metal girders positioned parallel to the leading edge of the airfoil, the girders being provided with a plurality of respectively equal spaced openings along their longitudinal web axes, a plurality of metallic curvilinear shaped ribs having a wave-like shape, the wave outline of each rib being of opposite direction from that of any adjacent rib, said ribs adapted to pass through said openings and to be fused to each girder and surfacing material adapted to be supported upon the flanges of said girders.
10. In an airfoil a plurality of girders positioned parallel to the leading edge thereof, the girders being provided with a plurality of respectively equal spaced openings along the longitudinal axes of their webs, a plurality of curvilinear shaped ribs, a wave-like shape the outline of each rib being opposite in direction to that of any adjacent rib, the leading and trailing edges of each rib being shaped to conform to the contour of the airfoil, said ribs adapted to pass through said openings and to be secured to each girder and surfacing material adapted to be supported upon the leading and trailing edges and the crests and troughs of each rib and upon each girder flange.
11. In an airfoil, a plurality of metal girders positioned parallel to the leading edge thereof, the girders being provided with a plurality of respectively equal spaced openings along the longitudinal axes of their webs, a plurality of metallic ribs of curvilinear outline, having a wave-like shape, the outline of each rib, being of opposite direction to that of any adjacent rib, the leading and trailing edges thereof being shaped to conform to the contour of the airfoil, said ribs adapted to pass through said openings and to be fused to the girders, and sheet metal surfacing material adapted to be supported upon and fused to the leading and trailing edges and the crests and troughs of the ribs and the flanges of the girders.
12. An airfoil comprising a plurality of girders positioned parallel to the leading edge thereof, the girders being provided with a plurality of respectively equal spaced openings along their longitudinal web axes, a plurality of curvilinear shaped ribs, each rib outline comprising a series of waves of varying lengths and amplitudes, the leading and trailing edges thereof being shaped to conform to the contour of the airfoil, said ribs adapted to pass through said openings and to be secured to the girders, and surfacing material adapted to be supported upon said ribs, and the flanges of said girders.
13. An airfoil comprises a plurality of metal girders positioned parallel to the leading edge thereof, the girders being provided with a plurality of respectively equal spaced openings along their longitudinal web axes, and plurality of metal ribs of curvilinear shape, each rib outline comprising a series of waves of varying length and amplitude, the leading and trailing edges thereof adapted to conform to the shape of the airfoil, said ribs adapted to pass through said openings, and to be fused thereto, and metallic sheet surfacing material adapted to be supported upon and fused to the ribs and to the flanges of said girders.
14. In an airfoil, a plurality of girders

positioned parallel to the leading edge thereof, the girders being provided with a plurality of respectively equal spaced openings along their longitudinal web axes, a plurality of ribs having a curvilinear outline of wave-like shape, the wave outline of each rib being opposite in direction to that of any adjacent rib and comprising a series of waves of varying lengths and amplitudes, said ribs adapted to pass through said openings and to be secured to each girder and surfacing material adapted to be supported upon the ribs and the flanges of the girder.

15. In an airfoil a plurality of metal girders positioned parallel to the leading edge thereof, the girders being provided with a plurality of respectively equal spaced openings along their longitudinal web axes, a plurality of metallic ribs having a curvilinear outline of wave-like shape, each rib having a wave outline opposite in direction to that of any adjacent rib and comprising a series of waves of varying lengths and amplitudes said ribs adapted to pass through said openings and to be fused thereto and sheet metal surfacing material adapted to be supported upon and fused to the ribs and the girder flanges.

16. A one piece continuous rib for an airfoil, adapted to extend transversely from the leading to the trailing edge of said airfoil, the forward end of said rib being bent backwardly towards the trailing edge of the airfoil in such a shape as to conform to the airfoil contour.

35 17. A one-piece continuous rib for an airfoil adapted to extend transversely from the leading edge to the trailing edge of said airfoil, the forward end of said rib being bent backwardly towards the trailing edge of the airfoil, the rearward end of said rib being bent forwardly towards the leading edge of the airfoil, both of said bends being of such shape as to conform to the airfoil contour.

45 18. A one-piece continuous rib for an airfoil, said rib having a curvilinear outline comprising crests and troughs, adapted to support the surfacing material of the airfoil, the rib extending transversely of the airfoil from its leading to its trailing edge, the forward end of said rib being bent backwardly towards the trailing edge of the airfoil, the after end of said rib being bent forwardly towards the leading edge of the airfoil, said bends being so shaped as to conform to the contour of the airfoil and adapted to support the surfacing material adjacent thereto.

In testimony whereof I affix my signature.
HARRY H. SEMMES.
